Primary Examiner — Eric Goodman*Assistant Examiner* — Daniel J Domino(74) *Attorney, Agent, or Firm* — Polster, Linder, Woodruff & Luccheni, LLC(57) **CLAIM**

The ornamental design for a pipe clamp, as shown and described.

DESCRIPTION

FIG. 1 is a view in perspective of a pipe clamp in accordance with my design.

FIG. 2 is a view in right side elevation thereof.

FIG. 3 is a view in left side elevation thereof.

FIG. 4 is a rear elevation thereof.

FIG. 5 is a front elevation thereof.

FIG. 6 is a top plan view thereof; and,

FIG. 7 is a bottom plan view thereof.

The broken line showing is included for the purpose of illustrating portions of the article and forms no part of the claimed design.
